DESIGN FOR A SMOKER'S TABLE OR THE LIKE

Pearl Ann Davis, Los Angeles, Calif.

Application July 31, 1944, Serial No. 114,663

Term of patent 7 years

(CL. D85—2)

To all whom it may concern:

Be it known that I, Pearl Ann Davis, a citizen of the United States, residing in Los Angeles, in the county of Los Angeles and State of California, have invented a new, original, and ornamental Design for Smoker's Table or the Like, of which the following is a specification, reference being had to the accompanying drawing, forming a part thereof.

In the drawing:

Fig. 1 is a perspective view of a smoker's table, showing my new design as it appears with the pipe rack, ash tray compartment, and the newspaper and magazine racks in extended position. The table lamp is integral with the top of the table.

Fig. 2 is an elevational view of the table as seen from the right of Figure 1 with the pipe rack and ash tray compartments in closed position.

Fig. 3 is a side elevational view of the table shown in Figure 1.

I claim:

The ornamental design for a smoker's table or the like, substantially as shown and described.

PEARL ANN DAVIS.
